US0D1069819S

(12) **United States Design Patent** (10) Patent No.: **US D1,069,819 S**
(45) Date of Patent: ** Apr. 8, 2025

(54) **DISPLAY SCREEN OR PORTION THEREOF WITH GRAPHICAL USER INTERFACE**

(71) Applicant: **The PNC Financial Services Group, Inc.**, Pittsburgh, PA (US)

(72) Inventors: **Dennis Michael Degnan, Jr.**, Pittsburgh, PA (US); **Stephanie Elizabeth Rodgers**, Dublin, OH (US); **Vorachat Tamarree**, Pittsburgh, PA (US); **Cyrus Ahmadi-Tehrani**, Seattle, WA (US); **Rostislav Rybalov**, Pittsburgh, PA (US); **Joseph Asher Friedman**, Pittsburgh, PA (US); **Lindsey Marie Boyko**, Bethel Park, PA (US); **Erin F. Holland**, Pittsburgh, PA (US)

(73) Assignee: **The PNC Financial Services Group, Inc.**, Pittsburgh, PA (US)

(**) Term: **15 Years**

(21) Appl. No.: **29/884,866**

(22) Filed: **Feb. 16, 2023**

Related U.S. Application Data

(63) Continuation of application No. 29/868,222, filed on Nov. 25, 2022.

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The broken lines of uneven length in the FIGURE show the display screen and form no part of the claimed design. The broken lines of even length in the FIGURE form no part of the claimed design. Stippling shown in the FIGURE illustrates a contrast in appearance.
